H. W. MANNING,
OIL BURNING APPARATUS.
APPLICATION FILED DEC. 15, 1919.

1,409,880.

Patented Mar. 14, 1922.

UNITED STATES PATENT OFFICE.

HARRY W. MANNING, OF PORTLAND, OREGON.

OIL-BURNING APPARATUS.

1,409,880.

Specification of Letters Patent. Patented Mar. 14, 1922.

Application filed December 15, 1919. Serial No. 345,158.

To all whom it may concern:

Be it known that I, HARRY W. MANNING, a citizen of the United States, and a resident of Portland, county of Multnomah, State of Oregon, have invented a new and useful Improvement in Oil-Burning Apparatus, of which the following is a specification.

My invention relates to oil burning apparatus as used in domestic service, and supplied from a tank under pressure.

The object of my invention is to render such apparatus safe by automatic means preventing accidents.

15 The flow of oil thru conduit or "hollow wire" connecting the tank with the burner must necessarily be controlled by fuel valve. And in the accidental opening of such valve while the burner is not operating resides a 20 constant highly dangerous condition. Such condition not infrequently is occasioned when the burner goes out for lack of fuel in the tank, and the latter is recharged without first closing the cut off valve in the 25 conduit. Then it may also happen that the wire conduit breaks and causes a flooding of the floor with fuel oil.

To prevent such accidents I provide in the conduit an automatic safety valve, that 30 is a check valve, which is adapted to be closed by the pressure of the fuel oil under tank pressure through the valve, and in this way cutting off the flow of the fuel oil until the pressure of the fuel-oil vapor generated 35 in the burner is sufficient to balance the tank pressure. And in order to permit the flow of some fuel oil into the burner when starting the latter, I provide manual means for forcibly opening the safety valve against 40 the tank pressure. These opening means are preferably spring controlled, and the spring is made to offer substantial resistance so as to require the application of substantial physical force—more than a child 45 would ordinarily exert—in order to forcibly unseat said check valve; and the moment the pressure is released on the valve opening means, the check valve should again act normally.

50 The construction of the parts included in my invention as well as the operation of my invention are illustrated in the accompanying drawings.

Fig. 1 diagrammatically represents a 55 heating apparatus of the type in mind com-

prising a tank of fuel oil under pressure, a burner, a conduit connecting the tank with the burner, and my safety valve installed in the conduit as in practice;

Fig. 2 is a view of my safety valve and associated parts looking in the direction indicated by the arrow 2 of Fig. 1;

Fig. 3 is a larger scaled sectional elevation of those parts included in the space enclosed by the broken line 3 in Fig. 1; 65 and

Fig. 4 is a larger scaled sectional elevation of the parts enclosed by the broken line 4 of Fig. 2.

a represents the usual supply tank which 70 is placed under pressure by the usual pump. b represents a hydrocarbon burner. The burner may be of any convenient type. That shown in Fig. 1 represents a type invented and marketed by me; such burner 75 being described in detail in my accompanying application for Letters Patent filed in the United States Patent Office Dec. 15, 1919, Serial No. 345,157.

Briefly describing this burner, it may be 80 said to consist of a generator c, a gas-mixing chamber d, and burner heads e, e' supplied from the gas mixing chamber; the air admitted into the gas mixing chamber being regulated by a valve f. The tank a 85 is connected with the burner b by a manually operated cut-off valve h, a detail of which is shown in Fig. 4. It comprises a valve housing h' and a valve i provided with a hand-wheel j. The valve housing h' 90 is provided with a flange k so that it may be firmly attached to a support.

On the valve housing h' is mounted the housing l of my check valve. The latter consists of a chamber l' in which is contained a ball valve m. The housing of the check valve has an extension n in which is slidable a plunger o, having a stem p extending outward of, and beyond said housing. The stem p is provided with a disk q; 100 and a spring r bears against the disk, in so doing normally holding the plunger o withdrawn from the outlet orifice of the check valve. A stop-pin s transversely inserted in the plunger o, limits the lift of the coil 105 spring r.

As will have been noticed from Fig. 1, the conduit branch g connects with the cut-out valve h, and the conduit branch g' leads from the check valve l to the burner. 110

Parts not specifically described are mere details of mechanical construction, and self evident from the drawings.

When first starting up the burner, the valve *i* is opened, this permits the flow of oil to the check valve *l*, but cannot pass the latter. The burner is then preliminarily heated in any convenient way and when heated to the degree of vaporizing the fuel oil, the plunger is depressed so as to unseat the ball valve *m* for a second or two so as to permit some fuel to pass through the conduit into the burner. As soon as the burner vaporizes the oil, the pressure of the vapor will be sufficient to balance the pressure in the tank and in so doing permit oil to flow from the latter to the burner.

I claim:

1. The combination in an oil burning apparatus of a tank holding fuel oil under pressure, a hydro-carbon oil burner, a conduit connecting the two, a check valve, in the conduit normally closed by the pressure in the tank until such pressure is counter balanced by the back pressure of the vaporized fuel in the burner, manually operated means for forcing the valve open, and means resisting the operation of said valve-opening-means and normally placing the same in its inoperative position.

2. The combination in an oil burning apparatus of a tank holding fuel oil under pressure, a hydro-carbon oil burner, a conduit connecting the two, a check valve, in the conduit normally closed by the pressure in the tank until such pressure is counter balanced by the back pressure of the vapor-

ized fuel in the burner, manually operated means for forcing the valve open, and a spring resisting the operation of said valve-opening-means and normally placing the same in its inoperative position.

3. The combination in an oil burning apparatus of a tank holding the fuel oil under pressure, a hydro-carbon oil burner, a conduit connecting the two, a valve chamber in the conduit, such chamber provided with a valve seat at its forward end, a valve normally held on said valve seat by the pressure in said tank, whereby the flow of fuel to the burner is stopped until said pressure is counter balanced by the back pressure of the vaporized fuel in the burner, manually operated means for forcing said check valve from its seat, and means resisting the operation of said valve-opening-means and normally placing the same in its inoperative position.

4. The combination in an oil burning apparatus of a tank holding fuel oil under pressure, a hydro-carbon oil burner, a conduit connecting the two, a valve chamber in the conduit, such chamber provided with a valve seat at its forward end, a valve normally held on said valve seat by the pressure in said tank, whereby the flow of fuel to the burner is stopped until said pressure is counter-balanced by the back pressure of the vaporized fuel in the burner, manually operated means for forcing said check valve from its seat, and a spring resisting the operation of said valve-opening-means and normally placing the same in its inoperative position.

HARRY W. MANNING.
